UNITED STATES PATENT OFFICE.

WILLIAM G. BETZ, OF CHICAGO HEIGHTS, ILLINOIS, ASSIGNOR OF ONE-THIRD TO
VIRGIL H. LOCKWOOD, OF INDIANAPOLIS, INDIANA.

MUSIC-TRACKING DEVICE FOR PNEUMATIC PIANOS.

1,201,925.

Specification of Letters Patent. Patented Oct. 17, 1916.

Application filed October 18, 1911. Serial No. 654,548.

To all whom it may concern:

Be it known that I, WILLIAM G. BETZ, a citizen of the United States, and a resident of Chicago Heights, county of Cook, and State of Illinois, have invented a certain useful Music-Tracking Device for Pneumatic Pianos; and I do hereby declare that the following is a full, clear, and exact description thereof, reference being had to the accompanying drawings.

The object of this invention is to provide an improved means for automatically maintaining the music sheet in pneumatic pianos in proper alinement with reference to the air ports in the tracker bar. Such alinement has heretofore been maintained by means controlled by the edges of the sheet of music, but since the edges become worn from handling, such tracking means soon becomes inaccurate and unsatisfactory.

The chief feature of my invention consists in utilizing the perforations in the sheet of music for causing the proper tracking of the same, because they do not get worn and are accurately cut by a standard scale and will cause accurate tracking regardless of the irregularities of the edges of the sheet.

Another feature of my invention consists in utilizing pneumatic means controlled by the perforations in the music sheet for effecting and maintaining the proper adjustment of the tracker bar and sheet of music.

The nature of the invention will be understood from the accompanying drawings and the following description and claims.

In the drawings, Figure 1 is a front elevation of a portion of a pneumatic piano, with parts removed and parts broken away. Fig. 2 is a vertical section on the line 2—2 of Fig. 1. Fig. 3 is an enlarged front elevation of a portion of the tracker bar and the associated parts. Fig. 4 is a central vertical section longitudinally of the device through the double power pneumatic shown at the left-hand end of Fig. 1. Fig. 5 is a vertical transverse section through the tracker bar on the line 5—5 of Fig. 1. Fig. 6 is a front elevation of a portion of the tracker shown in Fig. 3 but on a larger scale.

In detail there is shown a perforated music sheet 10, such as is usual in pneumatic pianos, and which winds from the music roll 11 to the take-up roll 12. These

rolls are carried by the usual means mounted in side bars 13 and 14 which are connected at the top by a bar 15 and with the bottom thereof resting on the shelf board 16 of the piano. The foregoing parts may be made in any desired way, as their particular form and arrangement constitute no part of this invention and it is understood that said parts are associated with the usual elements of pneumatic pianos, which, however, are not here shown.

The tracker bar 20 is mounted in connection with a bar 21 so as to be slidable longitudinally of the device. The bar 21 is fixed in connection with the frame bars 13 and 14 and along its front surface has a dove-tailed groove in which a corresponding tongue 22 of the tracker board fits. The tracker board has the usual air ports 23 through it in communication with the usual suction tubes 24, which latter project through and are mounted in the bar 21.

Aside from the lateral adjustment of the tracker bar, it has a further novel characteristic of being provided with a pair of longitudinal air channels 25 extending longitudinally thereof, substantially above the series of air ports 23, as shown in Figs. 2 and 5. The channels 25 which are at the left-hand end of the device, as shown in Fig. 1, are in communication with tubes 26 and at the right-hand end of the device said channels 25 are closed at the outer end. Small ports 27 lead from said channels 25 to the front surface of the tracker bar, as shown in Figs. 1, 2 and 3, there being two of said ports 27 for each main air port 23, there being one pair of said ports 27 above and between each adjacent pair of ports 23. One port 27 is in vertical alinement with one lateral edge of a main port 23 and the other port 27 is in vertical alinement with the adjacent edge of the adjacent port 23, as appears in Figs. 1 and 3.

A connection formed of bars 29 and 31 extends from the left-hand end of one end of the tracker bar to a movable member 32 of the double power pneumatic 33 so that said power pneumatic can longitudinally adjust the position of the tracker board. The bars 30 and 31 are connected with each other adjustably so that they can be made any desired length to properly position the tracker board when the power pneumatic is in normal position.

Referring to Fig. 4 the double power pneumatic 33 is mounted in connection with a pouch board 34 and said pouch board 34 is secured to a valve plate 35 and to a metal plate 36 by screws 37, said metal plate being secured upon the shelf board by brackets 38 and screws 39. The double power pneumatic has the movable member 32 fulcrumed midway its ends on a rounded bar 41 which is secured to the pouch board 34 so that said movable member 32 can rock. Adjacent each end of the end portion of the rocking plate 32 there is the usual form of bellows forming two chambers 42 and normally each 15 of the bellows of the power pneumatic is partially collapsed, substantially as shown, so that the movable member of the double power pneumatic can rock to some extent, as shown by dotted lines in Fig. 4, in either 20 direction and when rocked to its limit in one direction one of the bellows will be expanded and the other collapsed. Between the plates 34 and 35 there is an air chamber 43 which is in communication with the main 25 air reservoir of the instrument through a port 44. Also said air chamber 43 is in communication with each of the chambers 42 of the power pneumatic through a port 46, a passageway 47 and port 48. The port 46 30 is controlled by a valve 50 on a stem 51 which is held normally closed by a spring 52 held between nuts 53 on the stem 51 and secured on the metal plate 36. The valve 50 is opened by the pouch being actuated by air 35 entering the pouch chamber 55 through a passageway 56 and the tubes 26, heretofore described. Aside from the main air chamber 43 all of the parts in this construction are duplicated, as shown in Fig. 4. There 40 is a small ventilation hole 57 leading from each passageway 56 to the chamber 43 so as to release the pouch when air ceases to enter through the tubes 26. Therefore, when air enters either one of the tubes 26, air will be 45 withdrawn from the corresponding side of the double power pneumatic and the tracker bar longitudinally adjusted somewhat, in one direction or the other, according through which of the tubes 26 the air happens to enter.

Normally, and when the perforations of the music sheet are in direct alinement with their corresponding air ports 23, one or 55 more parts of each row of the small air ports 27 will be exposed, when the perforations in the music sheet come along and air will enter both tubes 26 alike and exhaust the air from both chambers 42 of the double power pneumatic equally and, therefore, 60 maintain the movable member 32 thereof, as shown in Fig. 4. If, however, the ports 23 of the tracker bar do not register accurately with the corresponding perforations in the music sheet so that one set of ports 27 65 would be closed by the music sheet and any

other ports 27 be opened through the perforations in the music sheet, air would pass only through the lower tube 26 and only the lower valve 50 would be actuated and air exhausted from the lower chamber 42 which 70 would cause the upper part of the upper power pneumatic to move the tracker bar correspondingly and bring it into proper alinement. The adjusting movement of the tracker bar would obviously be very slight, 75 but it would be constantly moved slightly one way or another, if necessary, to accommodate itself to any lateral or irregular movement of the sheet of music and thus maintain the openings in the said two parts 80 with proper alinement at all times and automatically.

I claim as my invention:

1. A player mechanism for musical instruments, comprising a traveling music sheet 85 provided with perforations disposed along parallel lines, a tracker bar provided with openings coöperating with the perforations of said sheet, and means controlled entirely by both side edges of a note perforation of 90 said sheet, by lateral shift of the sheet in either direction, for automatically preserving alinement thereof with the openings of 95 said tracker bar, operated only by air passing through said sheet.

2. A player mechanism for musical instruments, comprising a traveling music sheet provided with perforations disposed along parallel lines, a tracker bar provided with 100 openings coöperating with the perforations of said sheet, and means controlled by the opposite edges of each note perforation of said sheet, for automatically preserving alinement thereof with the openings of 105 said tracker bar, operated only by air passing through the perforations of the sheet, said means governed entirely by said edges for causing relative shift between the said sheet and tracker bar longitudinally of the latter.

3. A player mechanism for musical instruments, comprising a traveling music sheet provided with perforations disposed along parallel lines, a tracker bar provided with 115 openings coöperating with the perforations of said sheet, and means controlled entirely by both side edges of each and every note perforation of said sheet, by lateral shift of the sheet in opposite directions, for automatically preserving alinement thereof with 120 the openings of said tracker bar, operated only by air passing through said sheet.

4. A player mechanism for musical instruments, comprising a traveling music sheet provided with perforations disposed along 125 parallel lines, a tracker bar provided with openings coöperating with the perforations of said sheet, and means controlled entirely by both side edges of each and every note perforation of said sheet, by lateral shift 130

of the sheet in opposite directions, for automatically preserving alinement thereof with the openings of said tracker bar, said means including only two connections to said tracker bar, one for all right-hand edges and the other for all left-hand edges of said perforations.

5. A player mechanism for musical instruments, comprising a traveling music sheet 10 provided with perforations disposed along parallel lines, a tracker bar provided with openings coöoperating with the perforations of said sheet, and means controlled by both side edges of a note perforation of said sheet, 15 by lateral shift of the sheet in either direction, for automatically preserving alinement thereof with the openings of said tracker bar, and operated only by air passing through the perforation of the sheet, said 20 means having a series of holes in said tracker bar, and a passage in said tracker bar, intersecting said holes.

6. A pneumatic piano including a longitudinally movable tracker bar provided with 25 main air ports adapted to register with the perforations in a sheet of music for controlling the operation of the key actions of the piano and also provided with two series of small air ports so located in relation to the 30 main air ports and to each other that the admission of air thereto will be controlled by the perforations in the sheet of music, a conduit in communication with each series of small air ports, a double power pneumatic 35 including a rocking plate fulcrumed at its middle and constituting the movable member of said power pneumatic, one pneumatic of said double power pneumatic being located on each side of each fulcrum, the 40 two ends of said double power pneumatic being in communication respectively with said aforementioned conduits, and means for transmitting power from said power pneumatic to the tracker bar for causing its longitudinal adjustment.

7. A pneumatic piano including a longitudinally movable tracker bar provided with main air ports adapted to register with the perforations in a sheet of music for controlling 50 the operation of the key actions of the piano and also provided with two series of small air ports adjacent said main air ports,

said small air ports being arranged in substantially vertical alinement with the lateral and alternate edges of some of the main air 55 ports so that when the tracker bar is in proper registry with the sheet of music the perforations in the sheet of music will uncover one or more small air ports in each series thereof and when the same are not in 60 registry the small air ports of one series will be covered, a double power pneumatic, a passageway leading from each end of said power pneumatic to the corresponding series of 65 small air ports of the tracker bar, and connection between the movable part of the double power pneumatic and the tracker bar for longitudinally adjusting the latter.

8. The combination of a tracker bar containing apertures for effecting sound production, of a music sheet containing perforations, means for carrying said sheet over said tracker, and pneumatic mechanism comprising two sets of apertures adapted to coact with said perforations for maintaining 75 the registration of said perforations with said apertures first named, said second named apertures being partially uncovered when said perforations are in correct registration with said first named apertures. 80

9. The combination of a music sheet containing perforations, with a tracker mechanism containing a set of apertures coacting with said perforations to effect the production of musical sounds, and pneumatic mechanism for maintaining registration between said perforations and apertures, said pneumatic mechanism comprising ducts having apertures controlled by said sheet and adapted to communicate with perforations aforesaid, pneumatics having ducts connected therewith, a suction duct communicating with said ducts first named, and automatically operated valve mechanism for connecting said ducts first named with said ducts 85 second named. 90

In witness whereof, I have hereunto affixed my signature in the presence of the witnesses herein named.

WILLIAM G. BETZ.
